(57) **CLAIM**

We claim the ornamental design for a multi-use body wallet, as shown and described.

DESCRIPTION

FIG. 1 is a left, perspective view of the multi-use body wallet showing our new design;

FIG. 2 is an enlarged right side view with the strap attachments removed and the card holder flap raised;

FIG. 3 is a front view thereof;

FIG. 4 is a left side view thereof;

FIG. 5 is a reduced scale front view of the second embodiment of the design shown in FIG. 1

FIG. 6 is an enlarged, right side view with the strap attachments removed;

FIG. 7 is a front view of the card holder insert, which is detached for clarity of illustration and is the same design for the first embodiment of the claimed design;

FIG. 8 is a back view of the card holder insert;

FIG. 9 is a left side view with the card holder flap raised;

FIG. 10 is a left side view thereof; and,

FIG. 11 is a front view thereof.

The broken lines showing stitching are for the purposes of illustrating environment and form no part of the claimed design.
